UNITED STATES PATENT OFFICE.

WILLIAM H. PLUMB, OF ANSONIA, CONNECTICUT.

DESIGN FOR A SACHET OR PINCUSHION.

SPECIFICATION forming part of Design No. 21,490, dated April 19, 1892.

Application filed March 7, 1892. Serial No. 424,089. Term of patent 7 years.

To all whom it may concern:

Be it known that I, WILLIAM H. PLUMB, a citizen of the United States, residing at Ansonia, in the county of New Haven and State of Connecticut, have invented and produced 5 a certain new and original Design for Pincushions or Sachet-Cushions, of which the following is a full, clear, and exact specification.

10 The leading features of my design, which are shown in the drawing accompanying and forming a part of this specification, consist of the puffed and gathered bag-shaped body and the shell-shaped applied ornaments connected 15 together.

The body of the cushion is Shirred vertically, as at 1, gathered, as at 2, and at its top is provided with an outwardly-extending frill 3. 4 are applied ornaments of the shape of a scallop shell, and between each pair of 20 ornaments is interposed a bow 5.

I claim—

The design for a sachet or pincushion, substantially as herein shown and described.

In testimony whereof I affix my signature in 25 presence of two witnesses.

WILLIAM H. PLUMB.
